CHARLES E. H. LLOYD, OF LOS ANGELES, CALIFORNIA.

LUBRICATING MECHANISM.

1,329,717.

Specification of Letters Patent.

Patented Feb. 3, 1920.

Application filed May 6, 1918. Serial No. 232,880.

To all whom it may concern:

Be it known that I, CHARLES E. H. LLOYD, a citizen of the United States, residing at Los Angeles, in the county of Los Angeles 5 and State of California, have invented new and useful Improvements in Lubricating Mechanisms, of which the following is a specification.

My invention relates more specifically to a 10 mechanism for delivering lubricants to the moving parts of engines or other mechanisms during their operation.

The prime object of my invention is to provide a power driven mechanism that will 15 successively and intermittently deliver a uniform charge of lubricant from a plurality of discharge ports to the working parts of mechanisms requiring such lubrication.

Another object of my invention is to provide 20 a lubricating mechanism in which the lubricant discharge ports will visually indicate the discharge of lubricants therethrough on their operation.

A further object is to provide a mechanism 25 in which the quantity of lubricant from each discharge port may be regulated and varied to suit the requirements of the various parts of the mechanism to which it is delivered.

A still further object is to provide a pressure regulating means, whereby the lubricant which is being forced through the mechanism will at all times be maintained 30 under a uniform pressure.

A final object is to provide a simple and 35 efficient mechanism that is unlikely to get out of order during an operation and which will be positive in its operation.

I accomplish the above objects by means 40 of the mechanism described herein and illustrated in the accompanying drawings, in which:

Figure 1 is a plan view of my device, parts being broken away and in section in 45 order to illustrate more clearly the various working parts.

Fig. 2 is a sectional view of the same, taken on line 2—2 of Fig. 1, looking in the direction indicated by the arrows.

Fig. 3 is an enlarged sectional view of 50 the pressure relief valve.

In internal combustion engines requiring lubrication of their various moving and working parts it has been found desirable 55 to provide a means, whereby the various moving or working parts may be supplied

with the exact quantity of lubricant necessary for their efficient operation.

Heretofore the main difficulty experienced with such mechanisms is that they do not 60 deliver the exact quantity required and, moreover, the pressure cannot be regulated so that the same is uniform.

By means of my mechanism I am enabled to deliver lubricants successively and 65 intermittently from a plurality of ports to the various working parts of mechanisms in the exact quantity required, and to maintain at all times a uniform pressure of the lubricant passing therethrough.

Referring more particularly to the drawings, my mechanism preferably consists of a rectangular metallic housing 5 having a bottom wall 6, top wall 7, side walls 8 and 9, and removable end closure plates 10 and 11, 70 said plates being secured to the housing in any suitable manner.

The operating mechanism which principally consists of a feeding and distributing means is located within housing 5 which 80 is here shown as rectangular in form. The bottom wall 6 and the lower portion of side wall 8 are considerably thicker than the other walls and are provided with longitudinally extending bores 15 and 16. Rotatably mounted in bore 15 is a feed screw 17 preferably provided with square threads arranged in helical form extending throughout its entire length with the exception of the two ends. One end of screw 17 is provided with a stem 18 which extends through a packing box 19 of usual construction mounted in end plate 11, and has secured thereto a driving pinion 20, the stem being connected to a suitable source of power (not 90 shown).

Mounted in the other bore 16 is a hollow lubricant discharge cylinder tube 22, one end being provided with a stem or shaft 23 which extends through a packing box 24, the end of the stem having a driven pinion 25 rigidly secured thereto and meshing with the driving pinion, the driven pinion being of a ratio of approximately two to one of the driving. Discharge cylinder 100 tube 22 is preferably provided with a plurality of radial bores or ports 26 arranged in helical form. These ports, when the discharge cylinder is rotated, register successively with a plurality of threaded ports or 105 openings 27 formed in the lower portion of wall 8 of the housing.

Secured in the threaded ports or openings 26 are a plurality of lubricant feed indicating devices 28, and as they are exactly similar in construction only one will be described. Indicating device 28 preferably consists of a stem 30 having a central bore 31 therethrough, the outer end of said bore extending upwardly and terminating in an enlarged discharge outlet 32, the bottom 10 wall of which is inclined. The outer end of stem 30 is enlarged, as clearly shown in Fig. 2 of the drawings, and is preferably circular in form, the upper annular edge being threaded for the reception of a circular cap 35, provided with an opening in which is disposed a disk 36 of transparent material, the space between the upper face of the enlargement and the transparent disk 36 forming a display chamber 37 for the 15 lubricant which is forced through the bore 31. Projecting downwardly from the under face of the enlarged end of stem 30 is an externally threaded boss 38, a bore 39 passing therethrough and communicating 20 with the chamber 37, the bore 31, chamber 37 and bore 39 forming a continuous passage for the discharge of the lubricant from the hollow cylinder 22, a pipe 40 conveying the lubricant to a particular part of the 25 mechanism requiring lubrication. Disposed in chamber 37 and seating on the upper end of bore 31 is a small steel ball 41 adapted to be forced outwardly into the chamber 37 on a passage of lubricant through the indicating device. 30

Each of stems 30 are provided with a regulating valve 42, the lower end of the valve stems 43 engaging a seat 44 formed in the bore 31 on a rotation of the stems 43 40 downwardly, as best shown in Fig. 2 of the drawings. It will thus be seen that by means of these valves 42 I can regulate the passage of the lubricant through the various stems so as to suit the requirements of 45 the parts to which the lubricant is being distributed.

By means of steel ball 41 I am enabled to determine whether the lubricant is passing through pipe 40 to the mechanism requiring lubrication, the ball being forced 50 upwardly off its seat into the chamber 37 on a passage of the lubricant therethrough.

The upper wall 7 of the housing is provided with an inlet opening 45 in which is mounted a funnel 46 through which the lubricant may be introduced into the chamber 47 of the housing from time to time as required. The lubricant in the chamber 47 enters bore 15 through a port 48 and is 55 forced forwardly by the rotation of the feed screw 17 passing through port 50 formed in the wall dividing the two bores 15 and 16 at one end of the machine. The cylinder 22 at one end thereof is provided 60 with a plurality of ports 51 which register

from time to time with port 50 during the rotation of cylinder 22, admitting therethrough lubricant to the interior of cylinder 22 through which it passes through the ports 26 to the indicating devices, and 70 thence through pipe 40 through the various portions of a machine being lubricated. Bores 15 and 16 at one end thereof are provided with closure disks 52, 53, by means of which the end thrust of feed screw 17 75 and cylinder 22 may be regulated.

In order to provide for excess pressure of the lubricant passing through the mechanism, so that when the cylinder 22 is receiving an excessive amount, I have provided a discharge port 54 through end plate 10 and communicating with port 50, a pipe 55 provided with suitable fittings returning the excess lubricant and discharging the same into funnel 46 into the chamber 47. 80 From the above it will be noted that no matter how fast the feed screw 17 forces the lubricant through port 50 into the cylinder 22, any excess pressure will be relieved and taken care of by the return 85 pipe 55.

In order to regulate the pressure of the lubricant which is forced through the apparatus by means of the feed screw 17, I have provided a resiliently operated valve 90 mechanism in pipe line 55 adjacent end plate 10, as clearly shown in Fig. 1 of the drawings. This valve means consists of a semi-spherical seat 56 on which is seated a steel ball 57, the upper end of the fitting 58 100 being interiorly threaded for the reception of a screw plug 59, a coiled spring 60 being interposed between the ball and the screw plug 59 according to the pressure delivered by the feed screw 17, the ball pressure overcoming the tension of the spring when the pressure is excessive and forcing the same off its seat, allowing the lubricant to return through pipe line 55 to chamber 47, a dust proof cap 61 being provided at 110 the upper end of fitting 58.

The operation of my mechanism will be clearly apparent from the foregoing description.

Lubricant is introduced to the chamber 47 115 in a sufficient quantity to fill the same, and power is applied to the feed screw to rotate the same. As the lubricant is fed forwardly by the screw into cylinder 22, as heretofore explained, the valves 42 are regulated so 120 that the proper amount of lubricant will be discharged therethrough as required by the parts being lubricated. At the same time the tension of spring 60 is regulated by means of the screw plug 59 so that if a pressure of the lubricant being delivered by the feed screw is excessive, the same may be returned by pipe line 55 to the lubricant chamber. 125

From the above description it will be at 130

once apparent that I have provided a power driven lubricating mechanism that forces the lubricant through the discharge ports in cylinder 22 in an even and uniform manner, the indicating devices showing the operator at a glance each discharge of the lubricant therethrough.

What I claim is:

1. A lubricating mechanism, comprising a fluid chamber, a rotary fluid pumping means mounted in said chamber, a fluid distributing means also mounted in said chamber, said distributing means connected to said pumping means and adapted to deliver fluid from said chamber intermittently, and means to operate said pumping and distributing means.
2. A lubricating mechanism, comprising a fluid chamber, a rotary fluid pumping means mounted in said chamber, a fluid distributing means also mounted in said chamber, said distributing means connected to said pumping means and adapted to deliver fluid from said chamber, means to relieve excessive pressure of the fluid passing through said distributing means, and means to operate said pumping and distributing means.
3. A lubricating mechanism, comprising a fluid chamber, a fluid pumping and distributing means mounted in said chamber adapted to deliver fluid from said chamber intermittently, means to relieve excessive pressure of the fluid passing through said chamber, said chamber being provided with a plurality of ports in one wall thereof adjacent said distributing means, a fluid indicating device connected to said ports, said device adapted to visually indicate the passage of fluid through said ports, and means to operate said pumping and distributing means.
4. A lubricating mechanism, comprising a fluid chamber, a fluid pumping means mounted in said chamber, a fluid distributing means comprising a rotary cylinder provided with a plurality of ports arranged in helical form, said chamber adjacent said distributing means being provided with a plurality of outlets adapted to register with the ports in the distributing means, whereby fluid will be delivered from said distributing means through said bores intermittently and successively, means to relieve the excessive pressure of the fluid passing through said distributing means, and means to operate the pumping and distributing means.
5. A lubricating mechanism, comprising a casing forming a lubricant supply chamber,

a rotary lubricant pumping means mounted in said chamber, a valve distributing means mounted in said chamber and connected with said pumping means, said distributing means adapted to deliver lubricants successively and intermittently through a plurality of ports formed in a wall of said casing adjacent said distributing means, and means to operate said pumping and distributing means.

6. A lubricating mechanism, comprising a casing forming a lubricant supply chamber, a rotary lubricant pumping means mounted in said chamber, a lubricant valve distributing means mounted in said chamber adjacent said pumping means and connected therewith, a wall of said chamber being provided with a plurality of lubricant discharge ports, said ports communicating with said distributing means, and means to operate the pumping and distributing means simultaneously.

7. In a mechanism of the class described, a fluid chamber having a pair of longitudinally inclosed cylindrical bores therein, a screw pump rotatably mounted in one of said bores, a cylindrical fluid distributing tube having a plurality of outlets arranged in helical form mounted in the other of said bores, said bores communicating at one end thereof, the pumping bore having a fluid inlet leading from said fluid chamber, a spring pressed valve for relieving excess fluid pressure connected to said bores, means for regulating the tension of said spring pressed valve, a plurality of fluid outlet tubes mounted in a wall of said chamber and registering with the outlet formed in the distributing tube on a rotation thereof, said outlets in said tube registering with outlet tubes successively, valve means mounted in said outlet tubes to regulate the discharge therefrom, an indicating means mounted on each of said outlet tubes to indicate the discharge of lubricants through said tubes, and means to drive said screw pump and distributing tube simultaneously.

8. A lubricating mechanism, comprising a fluid supply chamber, a rotary fluid pumping means mounted in said chamber, a rotary fluid distributing means mounted in said chamber and in communication with said pumping means, and means to operate said pumping and distributing means.

In witness that I claim the foregoing I have hereunto subscribed my name.

CHAS. E. H. LLOYD.
